UNITED STATES PATENT OFFICE.

HERMAN H. BOETTCHER, OF BLUE EARTH, MINNESOTA, ASSIGNOR OF TWO-FIFTHS
TO W. H. BAIRD, OF MASON CITY, IOWA.

BEET-THINNING MACHINE.

Application filed February 6, 1928. Serial No. 252,324.

This invention relates to improvements in beet thinning machines and more particularly to an improvement in the machine illustrated and described in my co-pending application filed February 7, 1928, Serial No. 252,608, the object of the present invention being, as in the invention of the co-pending application, to provide a machine which will overcome the disadvantages of machines heretofore employed for this purpose and which will further present many marked advantages over the ordinary machines.

In the said co-pending application, as well as in the invention of the present application, a plurality of series of blades are arranged in an endless series and motion is imparted to the blades so that the blades, which are presented to the soil, will be traveling rearwardly at the same rate of speed as that at which the machine, in its entirety, is being advanced over the ground surface, the invention, in each instance, embodying means for effecting lateral travel of the blades so that they will move directly transversely across the furrows without, however, having any movement longitudinally of the furrows, and one of the objects of the present invention is to provide means for so supporting the blades that companion blades may be relatively adjusted so as to be spaced apart different distances so as to suitably relatively space the blades of each set in accordance with the width of the furrow to be acted upon by the blades, the invention likewise contemplating a relative adjustment of the blades and their supporting and actuating means at opposite sides of the machine in accordance with the spacing of relatively adjacent furrows.

Another object of the invention is to provide a novel construction of the endless rails about which the supports for the blades are caused to travel, which arrangement will provide for greater stability of the blades and the supporting means.

Another object of the invention is to provide novel means whereby the blade assemblies may be elevated and lowered with respect to the ground surface thus adapting the blades to be positioned at the proper elevation to act upon the beets in the furrows depending upon soil conditions and the depth of the furrows.

While the accompanying drawings and the

description which is to follow, constitute a disclosure of the preferred embodiment of the invention, it will be understood that various changes may be made within the scope of what is claimed.

In the accompanying drawings:

Figure 1 is a top plan view of the machine embodying the invention;

Figure 2 is a similar view, on an enlarged scale, of one side of the machine;

Figure 3 is a vertical front to rear sectional view taken substantially on the line 3—3 of Figure 2 and illustrating the construction and arrangement of one of the blade assemblies;

Figure 4 is a vertical front to rear sectional view taken substantially on the line 4—4 of Figure 2 looking in the direction indicated by the arrows and illustrating the manner in which the frame which supports the blade assemblies may be raised and lowered and likewise illustrating the means provided for imparting travel to the blade assemblies;

Figure 5 is a vertical transverse sectional view taken substantially on the line 5—5 of Figure 3 looking in the direction indicated by the arrows;

Figure 6 is a bottom plan view of the structure shown in Figure 5;

Figure 7 is a detail vertical transverse sectional view taken substantially on the line 7—7 of Figure 5 looking in the direction indicated by the arrows;

Figure 8 is a vertical transverse sectional view taken substantially on the line 8—8 of Figure 2 looking in the direction indicated by the arrows;

Figure 9 is a view similar to Figure 5 illustrating a slight modification of the invention.

As illustrated in the drawings, the machine includes, in its structure, a main frame 1 including a front sill 2, a rear sill 3, and side members 4, and arranged within this frame 1 is an auxiliary frame structure which is indicated in general by the numeral 5 and which comprises front and rear frame members indicated respectively by the numerals 6 and 7, these frame members being preferably of angle iron construction and the ends of the member 6 being bent to provide rearwardly extending side frame portions 8 and the ends of the member 7 being bent to extend for-

wardly and provide forwardly extending side frame portions 9. The frame members 8 and 9 are thence extended laterally as indicated by the numeral 10, in overlapped relation, and 5 secured to each other at their overlapped portions by bolts or other suitable fastening elements 11, the frame member 8, beyond the portion 10, being bent to extend rearwardly to provide an offset side frame member 12 10 which at its rear end is bolted or otherwise secured as indicated by the numeral 13, to the rear sill 3 of the main frame 1. The other frame section, beyond its portion 10, is bent to extend forwardly to provide an end frame 15 member 14 corresponding to the member 12 and extending in alinement therewith and bolted or otherwise secured at its forward end as at 15 to the front sill 2 of the main frame. The frame structure 5 further includes a rectangular frame which is arranged beneath the frame comprising the front and rear members 6 and 7 and the end members 8 20 and 9 and which includes front and rear members indicated respectively by the numerals 16 and 17, and end members which are indicated by the numeral 18, the members 16 and 17 being positioned directly beneath the front and rear members 6 and 7 of the upper section of the frame and the members 30 18 being positioned directly beneath the side members 8 and 9 of the upper frame section. Bearings 19 and 20 are mounted respectively between the upper side frame members 8 and 9 and the lower side frame member 18, similar bearings 21 and 22 being mounted beneath the side frame members 12 and 14, respectively, shafts 23 and 24 being journaled respectively in the bearings 19 and 20 and in the bearings 22 and 21 in the auxiliary frame 35 structure. Sprocket wheels 25 and 26 are mounted upon the shafts 23 and 24 respectively, and a sprocket chain 27 is trained about the said sprocket wheels 25 and 26. A sprocket gear 28 is also fixed upon the shaft 23 and a sprocket chain 29 is trained about this gear and about a sprocket gear 30 which is fixed 40 upon the axle of the machine which axle is indicated by the numeral 31. By reference to Figures 2, 4 and 8 of the drawings, it will be observed that the axle 31 is journaled at 45 its ends in bearings 32 which are mounted upon the side members 33 of auxiliary frames which are located at the ends of the main frame 1, each auxiliary frame being hingedly mounted at its forward end as indicated by 50 the numeral 34 upon the under side of the front sill 2 of the main frame. The end portion of the axle 31 which extends between the bearings 32 upon the side members 33 of each 55 auxiliary frame, supports a ground wheel indicated by the numeral 34', the hub 35 of which is provided at one side with rack teeth 36. A collar 37 is keyed upon the said portion of the axle for rotation therewith and at the 60 same time is slidably adjustable upon the axle

and is provided at one side with teeth 38 for coaction with the said teeth 36, the collar 37 being held in position with its teeth engaging the teeth of the hub 35, through the medium of a tension spring 39. At this point it will be 70 evident that the collars 37 are normally held, by the spring 39, in engagement with the hub 35 of the wheel 34', so that, as the machine is drawn over the field, the rotation of the ground wheels will effect rotation of the axle 75 31, and, due to the provision of the gear 30 upon the axle and the connection of this gear, by the sprocket chain 29, with the sprocket gear 28 upon the shaft 23, rotary motion will be imparted to the sprocket wheel 25 and consequently travel will be imparted to the sprocket chain 27. It will be understood that, in making turns, the inner ground wheel, at the turn, may rotate backwardly or 80 there may be a slippage of the teeth of the collar 37 past the teeth 36 upon the hub 35 of the said wheel. 85

As stated, the bearings for the axle 31 are mounted upon the side members 33 of the auxiliary frames, and means is provided connected with the free rear ends of these frames and mounted upon the rear sill 3 of the main frame, for maintaining the said rear free ends of the auxiliary frames at different elevations, the means being operable to effect 90 angular adjustment of the auxiliary frames and thus provide for elevation and lowering of the main frame and the frame structure 5 which is supported within the same, so as to properly position the blades of the machine 95 with respect to the ground surface. The means referred to includes a shaft 40 which is mounted in suitable bearings 41 upon the under side of the rear sill 3 of the main frame 1, this shaft having crank ends 42 located in rear of the said rear or free ends of the auxiliary frames and connected thereto by links 43. A hand lever 44 is fixed at its forward end to the intermediate portion of the shaft 40, and a pawl 45 upon the lever 100 coacts with a segmental rack 46 which is mounted upon the said sill 3 and in this manner the lever is held in different positions of angular adjustment, it being understood at this point that by adjusting the said lever 42, 105 the shaft 40 will be rocked so as to angularly adjust the crank arms 42 at the ends thereof and thus effect up and down swinging adjustment of the said auxiliary frames 33. 110

As in the above identified co-pending application, rods 47 are connected at their ends to the sprocket chains 27 and extend between the same, at suitable intervals, and these rods constitute supports upon which are slidably mounted sleeves which are indicated by the 115 numeral 48 and which support the blades of the machine, this invention differing from the invention of the said co-pending application in that, whereas in the co-pending application a pair of the blades are mounted 120

upon a single one of the sleeves, in the present application there are two of the sleeves provided and each individually supports one of the blades. The rods 47 of course extend 5 the entire width of the machine and between the sprocket chains at the opposite sides of the machine, and a pair of the sleeves 48 is slidably mounted upon each end of each rod 47. Each sleeve 48 supports a blade which is indicated by the numeral 49 and which is provided at its upper edge with shanks 50 which extend upwardly and through slots formed in laterally oppositely extending bracket arms 51 which are carried by the respective sleeve, it being observed by reference to Figures 5 and 6 of the drawings that the bracket portions 51 of the two sleeves 48 are located at corresponding ends of the sleeves and that the relatively adjacent ends of the 10 sleeves are spaced with respect to each other in the arrangement of the sleeves of each pair upon the respective rod 47. The shanks 50 of the blades 49 fit slidably through the slots in the bracket extensions 51, and compression 15 springs 52 are arranged to bear against the under sides of the bracket portions 51 of each sleeve and against the upper edge of the respective blade 49 inwardly of the shank portions 50, the blades being in this manner yieldably held in a lowered position for operative 20 engagement with the soil to dig and dislocate the beet or beets engaged by the blade, each blade being however capable of upward yielding movement in the event rocks or other non-yieldable obstructions are encountered in the 25 soil or in the event the soil is exceptionally hard. A brace 53 is hingedly connected at one end as at 54 to each blade 49 and is led upwardly beneath the respective sleeve 48 and 30 connected at its opposite end as at 55 to the said sleeve at that end thereof opposite the end at which the blade is located, each blade being in this manner braced against displacement and being yet capable of upward yielding 35 movement against the tension of the respective springs 52.

The sleeves 48 are slidable upon the rods 47 and in order that this movement of the sleeves may be automatically effected for the 40 purpose of shifting the blades 49 transversely of the line of travel of the machine, under conditions and in a manner to be presently explained, endless rails are provided and slides are mounted for travel over these rails and 45 are provided with means for the connection thereto of the said sleeves 48. The endless rails are indicated in general by the numeral 56 and, as shown in Figure 3 of the drawings, each rail includes an upper stretch 57, a lower stretch 58 which is substantially parallel to the upper stretch 57, and curvilinear end or connecting stretches indicated by the numeral 59, these latter stretches extending on arcs of substantially semi-circular extent and connecting the relatively adjacent ends of the 50 upper and lower stretches 57 and 58 of the respective rails. The rails 56 are arranged diagonally upon the frame 5 as illustrated in Figure 2, and by reference to said figure it will be understood that in addition to the pair 55 of rails illustrated therein, a similar pair will be located at the other side of the machine, and, as shown in Figure 3 of the drawings, the rails 56, which are of T-iron construction, are so arranged that their right angular 60 flanges will be presented inwardly and the rails are so disposed that the edges of these flanges at the curvilinear ends 59 of the rails will engage against the upper frame members 6 and 7 and lower frame members 16 and 17 65 of the frame structure 5, it being observed by reference to Figure 2 of the drawings that the horizontal flanges of the frame members 6 and 7 are formed with series of openings 60 for the passage of bolts 61 which bolts are 70 likewise engaged through openings in ears 62 formed upon the said flanges of the rails at the inner edges thereof, this arrangement providing for longitudinal adjustment of the rails upon the frame members 6 and 7 and 75 their attachment to these members in their positions of adjustment, it being understood that the rails of each pair may be relatively adjusted toward or away from each other in accordance with the width of the furrows to 80 be acted upon by the blades of the machine and that likewise the rails of the two pairs may be relatively adjusted to vary the distance between the same in accordance with 85 the relative spacing of the furrows.

In order that sliding movement of the sleeves 48 along the respective rods 47 may be effected automatically, in the travel of the chains 27, slides, indicated in general by the numeral 63 are mounted for travel upon the 90 rails 56 and one of these slides is associated with each of the sleeves 48 in a manner which will now be explained. Each slide comprises a plate 64 which is preferably of rectangular marginal contour and of a width equal substantially to the head of the respective rail 56, the said plate 64 being provided at its four corners with upstanding bracket portions 65, the bracket portions at the two sides of the plate extending upwardly beside the lateral edges of the rail head. An anti-friction roller 66 is journaled at its ends in openings in the bracket members 65 at each end of the plate 64 and the two rollers which are thus mounted upon each of the plates 64, ride 100 in contact with the surface of the head of the respective rail, it being observed by reference to Figures 3 and 5 of the drawings that in this invention the heads of the rails are presented outwardly and that the slides are 105 mounted upon the outer sides of the rails. Other anti-friction rollers 67 are mounted upon the bracket portions 65 at the ends thereof and travel in contact with the inner sides 110 of the heads of the respective rails. In order 115

120

125

130

to relieve the lateral thrust to which the slides may be subjected and to insure of more steady and even travel of the slides along the rails, a pair of brackets 68 is mounted upon the bracket members 65 at one side of each slide and anti-friction rollers 69 are journaled at the ends of these bracket members and ride against the outer edge of the head of the respective rail as clearly shown in Figures 5, 10 6 and 7 of the drawings. A circular plate 70 is rotatably disposed against the outer face of the plate 64 of each slide and connected at its axis to the plate 64 by a pin 71, so that the plate 70 may have rotative movement 15 with respect to the said plate 64, the plate 64 having guide lugs 72 stamped therefrom and bent to extend over the periphery of the plate 70 at diametrically opposite points thereof. The plate 70 is provided at opposite sides of 20 its axis with ears 73, and an arm 74 is provided at one end of each of the sleeves 48 and is disposed between the said ears 73 and connected by a pivot pin 75. At this point, and by reference to Figures 5 and 6 of the drawings, it will be observed that one sleeve of 25 each pair has its arm 74 located at that end opposite the end at which the blade 49 is located, whereas, in the instance of the other sleeve, the corresponding arm is located at the same end of the sleeve at which the blade 30 is located.

Figure 9 illustrates a slight modification of the invention as regards the connection between the blade supporting sleeves and the 35 slides which travel upon the endless rails, and in this figure the sleeve, which is indicated by the numeral 76 and which corresponds to the sleeve 48 previously described, is provided with an upstanding ear 77 located midway 40 between its ends, and this ear is pivoted as at 78 between a pair of depending ears 79 formed upon the under side of the plate 80 which corresponds to the plate 70 of the previously 45 described embodiment, the ears 79 corresponding to the ears 73, previously described. Otherwise the embodiment illustrated in Figure 9 is identical with that previously set forth.

The structure illustrated in Figure 2 of the 50 drawings, with the exception, of course, of the lever 44 and its associated parts, is duplicated at the other side of the machine, the rails 56 at the two sides of the machine being oppositely diagonally disposed. In the 55 operation of the machine and as the same is drawn over the field, motion is imparted to the rods 47 and sleeves 48 to effect travel of the guides along the endless rails, and the 60 gearing by means of which travel is imparted to the parts referred to, is so proportioned that the speed of travel of the blades, in a rearward direction, is precisely equal to the speed of travel of the machine, as a whole, in a forward direction, along the furrows so that, 65 so far as movement in the line of travel of

the machine is concerned, the blades are immovable with relation to the furrows. However, as the rails are diagonally disposed as stated above and the slides travel along the rails and therefore shift the sleeves 48 along 70 the rods 47 in the direction of the intermediate points of the rods, as the slides travel along the lower stretch of each rail 56, a lateral inward motion will be imparted to the blades 49 so that the blades will move directly 75 across the furrows on a line at right angles to the lines of extent of the furrows, thus digging through the furrows and removing the plants which are in the path of movement of the blades. It will be observed by reference 80 to Figure 3 of the drawings that the blades are arranged in a series of groups, a sufficient number of blades being provided in each group to insure of the removal of a predetermined number of plants or hills of 85 plants as the blades of each group are caused to move across the furrows, the groups being spaced apart a distance sufficient to provide against any disturbance of the soil in the furrows about corresponding hills in two furrows straddled by the rails of each pair, so that, as a consequence, the plants growing between two plants spaced apart a predetermined distance in the furrows, will be dug out 90 and the said spaced plants will be left standing. 95

It will be understood from the foregoing description of the invention that, inasmuch as each blade is independently mounted upon an individual sleeve which in turn is connected by an individual one of the slides with one rail of the pair, and the said rails are adjustable with respect to each other and likewise, in unison, longitudinally of the frame bars 6 and 7, the corresponding blades of 100 each pair of series may be spaced apart any desired distance in accordance with the width of the furrows, and, likewise, the blades of the assemblages at the opposite sides of the middle of the machine may be relatively adjusted 105 in accordance with the spacing of the furrows. 110

It will furthermore be evident, from the foregoing description, that the construction of the slides provides for uniform travel of 115 the sleeves 48 with the rods 47 by which they are supported and a uniform travel of the slides over the endless rails and particularly at the curvilinear end portions 59 thereof.

With reference to the arrangement of the 120 auxiliary frames with respect to the main frame and the mounting of the axle of the machine in these auxiliary frames, it will be evident that by operating the lever 44, the main frame may be bodily adjusted with respect to the said auxiliary frames and therefore the blade assemblages may be raised or lowered with respect to the ground surface 125 as is found necessary or desirable.

In the co-pending application, the slides to 130

which the blade supporting sleeves are connected, are mounted for travel upon the inner sides of endless rails, whereas the present invention constitutes an improvement inasmuch as the slides, as will be observed by reference to Figures 3 and 4 of the drawings, are supported for travel upon the outer sides of said rails, and, as a consequence, the blades are not only cushioned by the springs 52, but, furthermore, any upward thrust which may be imposed upon the blades or the slides as the latter travel along the lower section of each rail, will be effectually resisted inasmuch as the rollers 66 of the slides engage the said sections of the rails at their upper or outer sides.

Having thus described the invention, what I claim is:

1. A machine of the class described comprising a frame supported for travel, a pair of endless rails arranged parallel to each other and at an angle to the line of travel of the machine, in said frame, means connecting the rails with the frame to provide for relative adjustment of the rails transversely of the frame, blade supporting members extending transversely with respect to the rails and to the line of travel of the machine and arranged in an endless series, blades supported by said members, means for imparting motion to the series of blade supporting members and the blades carried thereby at a rate of speed such that the lower stretch of the series of members will travel in the direction opposite the direction of travel of the machine and at a rate of speed equal to the speed of travel of the machine, and operative connection between said rails and said blade supporting members for effecting movement of the members and the blades carried thereby in a direction transverse to the line of travel of the machine.

2. In a machine of the class described, spaced endless rails disposed parallel to each other and at an angle to the line of travel of the machine, means supporting the rails for adjustment with respect to each other to vary the distance between the rails, endless elements mounted for travel at opposite sides of the said rails, means for imparting motion to said elements, the elements being arranged in planes parallel to the line of travel of the machine, rods extending between said elements, a pair of supporting members upon each of the rods, blades supported by said members, and means carried by each supporting member and slidably engaging a respective one of the rails for effecting sliding movement of the supporting member on the respective rod.

3. In a machine of the class described, a frame supported for travel, spaced parallel endless rails supported by said frame and extending at an angle to the line of travel of the machine, means mounting the rails within the frame for adjustment with respect to each

other whereby to vary the distance between the rails, endless gear elements arranged at opposite sides of the rails, means for imparting travel to said gear elements in a direction opposite to the direction of travel of the machine and at a rate of speed equal substantially to the speed of travel of the machine, the gear elements traveling in planes substantially parallel to the line of travel of the machine, rods extending between said gear elements in an endless series and transversely of the rails, slides slidably mounted upon the rails, a pair of sleeves mounted slidably upon each of said rods, operative connection between each sleeve and a corresponding slide upon the respective rail, and blades carried by said sleeves, the connection of the sleeves with the respective rails and the angular disposition of the rails with respect to the line of travel of the machine effecting lateral sliding movement of the sleeves upon each rod and the blades carried thereby in the travel of the sleeves and blades.

4. A machine of the class described comprising a frame supported for travel, spaced endless rails, means mounting the rails within the frame for adjustment with respect to each other whereby to vary the distance between the rails, the said rails including upper and lower portions and arcuate connecting portions, the said rails occupying planes parallel to each other and at an angle to the line of travel of the machine, an endless series of rods supported for travel in unison and in position transversely of the rails, means for imparting travel to the series of rods, a pair of supporting members slidably mounted upon each of the rods intermediate the rails, a blade upon each supporting member, and operative connection between each supporting member and the respective rail for effecting automatic sliding movement of the supporting member along the respective rod in the travel of the rods about said rails, the motion transmitting means for the rods operating to impart travel to the lower stretch of the series of rods in a direction the reverse of the direction of travel of the machine and at a rate of speed equal substantially to the rate of speed of travel of the machine, the connection between each supporting member and the respective rail constituting means for effecting lateral movement of the respective blade transverse to the line of travel of the machine.

5. In a machine of the class described, a frame supported for travel, endless rails mounted in the frame and disposed in vertical parallel planes at an angle to the line of travel of the machine, means supporting the said rails in the frame for relative adjustment with respect to each other along the frame to vary the space between the rails, endless elements supported for travel at the opposite sides of the rails, rods extending

between said elements and transversely with respect to the rails, a pair of sleeves slidably mounted upon each rod, means for imparting motion to said elements to effect travel of the rods, slides each including a member slidably mounted upon a respective one of the rails and a member swiveled thereto, and operative connection between the swiveled members of the slides and the respective sleeves, and a blade carried by each of said sleeves.

6. In a machine of the class described, a frame supported for travel, endless rails mounted in the frame in planes parallel to each other and at an angle to the line of travel of the machine, pairs of sprocket gears arranged at the opposite sides of said rails, means supporting the rails within the frame for adjustment with respect to each other and with respect to the said sprocket gears, a sprocket chain trained about the gears of each pair, means for imparting rotary motion to the corresponding gear of each pair, rods carried by the chains and extending between the same and transversely with respect to the rails, a pair of sleeves slidably mounted upon each of said rods with one end opposing a respective one of the rails, a slide associated with each rail opposite the said end of a respective one of the sleeves and comprising a member having a plate portion and side portions extending at opposite sides of the respective rails, anti-friction rollers journaled between the side portions and in contact with the rails, other rollers mounted upon the inner sides of the side portions and overhanging and contacting the flanges of the respective rails, a plate member swiveled upon the plate portion of the first mentioned member of each slide, operative connection between the last mentioned plate member and the end of the respective one of the sleeves, and a blade carried by each of said sleeves.

7. In a machine of the class described, a main frame, a frame structure mounted within the main frame, the main frame being supported for travel, the said frame structure including upper and lower front and rear longitudinally extending members, a pair of endless rails each including a head and a continuous flange extending inwardly from the head, the flanges being secured to the said members of the second mentioned frame with the rails extending about said frame exteriorly thereof and with its head presented outwardly, a series of rods supported transversely of the rails, means for supporting said rods for travel about the said rails, sleeves mounted upon each of said rods for sliding movement, a blade carried by each of said sleeves, a slide associated with each sleeve and comprising a member having a plate portion and side portions, the latter extending beside the opposite sides of the head of the respective rail, anti-

friction means mounted between the said side portions and contacting the outer face of the head of the respective rail, a plate member swiveled to the first mentioned member, and operative connection between each plate member and the respective one of the sleeves.

8. In a machine of the class described, a main frame, an auxiliary frame mounted within the main frame, endless rails arranged in parallel planes to each other and at an angle to the line of travel of the machine, each of said rails including an endless head having upper and lower relatively straight stretches and curvilinear portions extending between the ends of said stretches, each rail being provided upon the inner side of its head with a continuous flange, the rails being disposed to extend about the said auxiliary frame structure and being secured thereto in spaced relation to each other, endless chains mounted for travel at the opposite sides of the rails, means for imparting travel to said chains, rods extending between said chains and transversely with respect to the said rails, slides slidably mounted upon the outer sides of the heads of the rails to travel therealong, a pair of sleeves upon each of said rods, each sleeve having its outer end connected with a respective one of said slides, and a blade carried by each sleeve.

9. In a machine of the class described, a main frame, an auxiliary frame mounted within the main frame, shafts journaled in the auxiliary frame, sprocket gears upon said shafts, a sprocket chain trained about each pair of gears, a pair of endless rails disposed to surround the auxiliary frame and arranged in planes parallel to each other and at an angle to the line of travel of the machine, rods extending between the said chains and transversely of the rails, sleeves slidably mounted upon said rods, slides mounted for travel upon the rails, operative connection between the slides and sleeves, a blade carried by each sleeve, a frame hingedly mounted in the main frame at the rear thereof and at each end, an axle journaled in the last mentioned frames, a ground wheel at each end of the axle within each of the last mentioned frames, a sprocket gear upon the axle at each end thereof, a second sprocket gear upon one of the first mentioned shafts, and sprocket chains trained about the last mentioned sprocket gear upon the axle and the said first mentioned gears, and means connected with the free ends of the last mentioned frames for simultaneously angularly adjusting said frames whereby to effect raising and lowering of the main frame.

10. In a machine of the class described, a frame supported for travel, endless rails mounted in the frame and disposed in vertical parallel planes at an angle to the line of travel of the machine, endless elements supported for travel at the opposite sides of the rails, rods extending between said elements

and transversely with respect to the rails, means for imparting motion to said elements to effect travel of the rods, supporting sleeves slidably mounted upon the rods, bracket members upon the sleeves, blades having spaced shanks slidably assembled with the bracket members, cushioning springs interposed be-

tween the bracket members and the blades and yieldably holding the blades extended downwardly beyond the bracket members, slides 10 mounted upon the rails, and operative connection between the slides and the sleeves.

In testimony whereof I affix my signature.

HERMAN H. BOETTCHER.
